OPERATING CONNECTION FOR CYLINDER LOCKS

Herbert Quigley, Hastings, Mich., assignor to National Brass Company, Grand Rapids, Mich., a corporation of Michigan

Application July 29, 1946, Serial No. 686,982

14 Claims. (Cl. 70—379)

1

The present invention is concerned with locks of the character or type generally designated as cylinder locks in which a bolt may be projected to a locked position or may be withdrawn to unlocked position by a manual operation at the inner side of the door and similarly operated by key at the outer side of the door.

Heretofore, in general with locks of the character noted in which the bolt is mounted for movement in a tubular housing the locking of the door from the outside necessitates turning the key a required number of degrees to move the bolt to its locking position and then the key must be reversely turned back to the position which it started in order that it may be removed. Similarly, to unlock the door the key is moved a like number of degrees in the opposite direction, thereby moving the bolt to its unlocked position and then the key must be returned to its starting position before it can be removed. The returning of the key to the starting position is confusing to the operator. Further, since no stops are provided to stop the key at the starting position, it has been necessary to locate this position by trial and error and by feeling, which is rather difficult and in general an annoyance.

Further, care has been required during the installation of the cylinder lock as there is a fixed relation of the parts and during installation they must be put together in accordance with indicating arrows on directions thereon. Unless this fixed relation of parts is made during installation, the installed cylinder lock will not properly operate. The present invention relates to a novel structure by means of which the key may be turned in one direction for projecting the bolt or in the opposite direction for retracting the bolt but such rotation of the key is through a full circle or 360° and further, such rotation is stopped at the proper position in either direction to permit withdrawal of the key. Furthermore, with the present invention the manual means at the inner side of the door for operating the bolt may be manipulated in either of its directions without affecting the key operated means. Installation is simplified as the need for indicating arrows on the parts is eliminated. The structure includes a novel escapement mechanism for effecting ease and certainty of operation, for moving the latch bolt both by manual operation at the inner side of the door and by key operation at the outer side.

It is a primary object and purpose of the present invention to provide a lock actuating structure effecting the purposes and functions

stated, which structure is readily manufactured and assembled, which is sure in use, sturdy and not liable to get out of order, and in which the assembly of the parts and the installation on the door is substantially foolproof, the workman not being required to carefully observe and follow certain steps of assembly and operation which, with other cylinder locks, have been necessary.

An understanding of the invention may be had from the following description, taken in connection with the drawings, in which:

Fig. 1 is a horizontal section through a fragmentary portion of a door and associated door casing showing the installation in conjunction with a cylinder lock in plan, with some parts in horizontal section.

Fig. 2 is an inner side view showing the case on which my invention is carried, the key operated bolt retracting and projecting means being shown in end elevation.

Fig. 3 is a vertical section substantially on the plane of line 3—3 of Fig. 2, the key operated structure of my invention being shown in side elevation.

Fig. 4 is a fragmentary vertical section through such key operated mechanism.

Fig. 5 is a fragmentary horizontal section through the structure shown in Fig. 4, said section being at right angles thereto.

Figs. 6 to 11 inclusive are somewhat enlarged elevations of the key actuated mechanism, the end elevation in Fig. 6 being of the assembled unit, and in the successive figures to and including Fig. 11 said unit having successive parts thereof removed.

Figs. 12 to 18 inclusive are transverse sections intermediate the front and rear sides of the key actuated unit, all of the sections being at the same plane, with the parts at the different positions which they take during key operation.

Fig. 19 is a fragmentary enlarged partial horizontal section and under plan view on a plane through the unit near the lower side thereof, and

Fig. 20 illustrates, in perspective, the parts or elements used, in separated or disassembled relation to each other.

Like reference characters refer to like parts in the different figures of the drawings.

In Fig. 1, adjacent the free vertical edge portion of a door 1, a cylindrical recess 2 is bored within which the tubular housing 3 of the cylinder lock structure is received. The mechanism within the housing is of conventional structure of the type used within housings of a cylindrical character. A bolt 4 is mounted for projection or

withdrawal by longitudinal movement thereof and when the door is closed, and the bolt projected outwardly, it passes through a keeper into a recess in the door casing 5. The door at the opposite sides has openings 6 extending to the interior recess 2. At the inner side of the door a manually operable knob or thumb piece 7, of conventional structure, is mounted, from which a short bar 8 extends into the interior of the housing 3. The thumb piece 7 and bar 8 permit manual operation, from the inner side of the door, of the bolt 4 either to its outer locking position or its withdrawn, unlocking position. It is to be understood that the knob or thumb piece 7 is turned in one direction to withdraw the bolt, and in the other to move it outwardly. The mechanism within the housing 3 actuated by the bar 8, and directly engaged by said bar, may be moved only through a half circle for such projection or retraction of the bolt. The structure thus far described comprises the environment with which my invention of the present application is used.

At the outer side of the door and covering the outer opening at 6 is a housing 9. The housing 9 is of a generally oval form, and at its central portion has an outwardly projecting part 10 within which a key operated lock is housed. Said lock includes a cylinder or barrel 11 mounted within a casing 13. The barrel 11 may be turned about its longitudinal axis by a key 12 inserted therein. From the casing 13 a wing or vane 14 extends radially in an upper direction, as shown. An upper post 15, through which a screw passes, secures the housing at the outer side of the door. A flat plate 16 is placed thereover and attached to said housing. Said plate has tongues 17, at its lower edge, struck and bent outwardly at opposite sides of the wing 14 (Figure 3) for securing said wing and casing 13 to said housing 9. It is to be understood that the lock itself is an old and well known structure having the usual tumblers which prevent any rotation of the barrel 11 when the key is withdrawn, the key moving them outward in recesses made therefor through the casing 13 and into the wing or vane 14 when it is inserted in the barrel at a predetermined position. A lower spacing post 18 is integral with the housing, through which a second screw passes in connecting it with the door.

At the inner end of the rotatable barrel 11, a plate 19 of a substantially circular form is secured. The plate 19, at its central portion and at its outer side, has a projection 20 of circular outline which seats against the inner end of the barrel 11 (Figs. 4 and 5). Screws, as shown in Fig. 5, pass through said plate 19 and are threaded into the barrel 11. Said plate 19 at the lower side thereof, as shown in Fig. 20, is recessed on two sides of a downwardly extending, triangular cam or projection 21. Two shoulders equally spaced from said projection are provided at the outer sides of said recesses.

A ring 22 of flat metal has a central opening of such size that the ring may be placed over the projecting portion 20. Said ring is of circular outline except at its lower side where it has a downward projection 23 provided with a shoulder at each side thereof. Said projection is also formed with a vertical slot 23a, the upper end of which communicates with the central opening of the ring 22. A ring member 24 of thin spring material is provided to be located against the outer side of the ring 22. Said ring member

24, at its lower portion, has a downwardly extending U-shaped section 25 which is distorted from the plane of the body of the ring, as shown. The opening through the ring member 24 and extending into the part 25 is slightly less in diameter than the exterior diameter of the ring 22 (Fig. 7) and the part 25 thereof is located below the lower edge of the projection 23.

Outwardly of the spring ring member 24, there is provided a plate 26 of flat, relatively rigid metal. The plate 26 has a generally circular outline except at its upper end where it extends upwardly for a short distance and is formed with two spaced tongues 27 bent at right angles to the plane thereof in an outward direction. Also around the periphery of the plate 26, shallow notches 28 are shown and the lower end portion of the plate has a downward extension 29 against the rear side of which the part 25 of the spring ring member 24 is seated. The plate 26 likewise has a central opening large enough in diameter that the case 13 of the lock may pass through it (Fig. 4). At the lower side of said central opening a tongue 30 is bent inwardly to pass through the spring ring member 24 and seat in the slot 23a of the ring 22. When the mechanism is installed and in use, the tongues 27 (Figs. 1 and 3) pass, one on each side of the fixed wing or vane 14. Therefore, in all turning movements of the key operated barrel 11, said plate 26 and the ring 22 are held against movement. Likewise the spring ring member 24 has no rotative movement but is held in a fixed relation to the ring 22 and plate 26 by structure hereinafter appearing.

Against the inner side of the circular plate 19, there bears a circular flange 31 of a cup member made from sheet metal. The cup 32 of said member extends inwardly and at its bottom has a diametrically located slot 33 (Figure 20). Two projections, wings or short tongues 34 extend from the flange 31 at diametrically opposed points and in substantial alignment with the slot 33. Said cup 32 of the cup member, at one side and a part of its bottom, and also an inner portion of the flange 31, is cut away as shown at 35. This cut away 35 (Fig. 5), in the mounting of the assembled structure at the inner end of the barrel 11, permits the screws which are used, to be passed through said opening at 35, one of them being first passed through and connected with the barrel 11 and then the cup turned through 180 degrees for the passage of the other screw used.

A flat bar 36, called a tail piece, having a head 37 at its outer end passes through the slot 33, the head coming against the bottom of the cup. Said bar 36 is like the bar 8 in cross section and is adapted to enter the barrel 3 at the opposite side of bar 8 for engaging the mechanism therein for retracting or projecting the latch bolt. The cup member 32 being connected by the bar 36 with the latch thus becomes the actuating member therefor.

At the inner side of the flange 31, there is located a coupling member or a ring 38 of flat rigid metal. At its lower side the ring 38 has an outwardly extending arm or finger 39 struck and bent to extend in an outward direction. The member 38 has a substantially elliptical periphery (Figs. 10 and 11) with a major axis substantially at right angles to the plane of the finger 39, said finger being located substantially at one end of the minor axis but extending downwardly a short

distance beyond what should be the end of the minor axis of a true ellipse.

The final member or element of structure used comprises a housing having an inner face 40 with housing sides 41 of a generally circular shape extending outwardly. The housing at its lower side is downwardly extended in the same manner that the plate 26 has its U-shaped, lower extension 29, and has sides 41a shaped to correspond. The inner face 40 has a central opening for the cup 32 to pass through (Fig. 5). The member 33 has a central opening of large enough diameter that said member 38 is permitted a limited degree of floating movement. Four tongues 42 extend outwardly from the inner edges of the housing sides 41, said tongues being spaced so that they may seat in the notches or recesses 28 of the plate 26. The central opening at the inner face 40 of the housing, at one side is notched at 43, so that the heads of the screws connecting the plate 19 to the barrel 11 may be passed therethrough for purposes of assembly.

The several parts described, all of which are shown separated in Fig. 20, are assembled within the housing, last described, in direct contact relationship with each other at their adjacent sides, excepting the tail piece 36 which has no contact with any part except the bottom of the cup-shaped member described. When thus assembled, the tongues 42 are all bent inwardly toward each other and against the outer sides of the plate 26 (Figs. 1 and 6), and all of the parts are securely held together, making a compact unit. Such unit, as previously described, is secured by means of the screws shown in Fig. 5 to the inner end of the barrel 11. The lower part 25 of the spring ring member 24 (Fig. 7) is located between the downwardly extending angular sides 41a of the housing and is held against rotation.

It is evident that the plate 19 will turn with the barrel 11 about the longitudinal axis of said barrel upon key operation of the barrel and that said plate 19 is free to move with the barrel 11.

Operation

With the parts in the position shown in Figs. 6 to 11 inclusive, and with particular reference to Figs. 8 and 9, the latch bolt has been retracted by turning the key in a counterclockwise direction indicated by the arrow in Fig. 8. The rotary movement of the key is accompanied by a similar continuous movement of the plate 19 since this plate is permanently secured to the barrel 11 which the key turns. A stop is provided by the finger 39 coming against a side of the projection 23 as shown, said finger being seated in a recess in the plate 19 at the left of the projection 21 as shown in Fig. 9. Therefore, when in the counterclockwise rotation of the plate 19 the plate's engagement with the finger 39 moves the member 38, movement is positively stopped by the finger or arm 39 coming against one end or side of the projection at 23.

To project the latch bolt to locking position, the parts are rotated in the opposite direction or clockwise as indicated by the arrows in Figs. 12 to 16 inclusive. With such movement in a clockwise direction, plate 19 is turned, moving its projection 21 from the position indicated in Fig. 9 to the left over said finger 39, thus, moving the finger 39 downwardly to the lower part of the pocket or lower extension at 41a of the housing sides 41, as in Fig. 12. The plate 19 is thereupon freed for a continuation of movement clockwise

with projection 39 lying in the right hand recess of plate 19. Thereupon a continuous turning movement of the plate 19 clockwise, moves finger 39, and the member 38 to which it is connected, with said plate 19. Because the finger 39 rides against the inclined left hand side of the housing walls 41a, said member 38 is moved back allowing said finger 39 to move within the circular outline of the fixed guide or housing sides 41, the initiation of which is shown in Fig. 14.

The parts 19 and 38 may then be continued in movement in a clockwise direction until as shown in Fig. 15, said finger 39 comes against a side of a wing or projection 34 on the cup member 31. Such contact occurs after the key and the parts connected directly therewith have moved through substantially 180° of movement. Upon further movement from the position shown in Fig. 15 to that in Fig. 16 said finger 39 carries the projection 34 ahead of it until the finger 39 is brought against the opposite side of the stop at 23. During the latter half of such movement, inasmuch as the cup member is turned, the bar 36 is likewise turned and projects the latch bolt. At this stopping position, after the complete rotation of the key, the key may be removed from the lock. Also this stopping position, when the finger 39 has come against the part 23, at one side thereof, it rides over a rise or hump in the spring ring member 24 (Fig. 19) which hump tends to yieldingly hold said finger and the parts connected therewith against aimless or undesired rotative movement in the opposite or any direction. Said spring ring member holds finger 39 to allow camming of it by the projection 21, and the beveled ends of the projections 34 will engage therewith.

In Figs. 17 and 18, after the parts have reached the stopping position illustrated in Fig. 16, if the key is turned in the opposite direction or counterclockwise, the projection 21 will ride over and push the finger 39 into the lower extension 41a of the housing and out of contact with the stop member 23 thereupon. Except for the interposition of the stop provided by the bolt operating mechanism within the tubular housing 3, a continuation of movement in a clockwise direction as in Fig. 18 would be possible, as the finger 39 has been moved out of the position where it must engage with the stop 23. Such continuation of movement and rotation of the parts first through a complete rotation clockwise, a short reverse rotation counter-clockwise and then a continuous rotation clockwise until stopped permits an assembly of the parts 19, 38 and the cup member 32 and its flange 31 without reference to any exact positions in which they must be placed with respect to the other parts, the key operated mechanism, when disconnected from the bolt mechanism being turnable back and forth until the various parts housed between the plate 26 and the bottom 40 of the inner housing member take their proper positions relative to each other. Furthermore, there is permitted absolute freedom of the operation of the bolt by the manually engageable member 7 at the inner side of the door in either direction required.

After the bolt has been moved outwardly to its locking position, shown in Fig. 1, and with the parts arranged as shown in Fig. 16, the bolt is retracted by turning the key in the opposite direction. During the first half circle of rotation no movement is imparted to the bolt. After the half circle of rotation the finger 39 engages the right hand side of the projection 34 and thereafter carries the cup member with it, operating the

mechanism within the bolt housing 3 to withdraw the bolt. This rotation continues until it is stopped by the finger 39 coming against the opposite side of projection 23 as shown in Fig. 8.

The bar or tail piece 36 by its connection with the bolt, operates said bolt either in moving to locked or unlocked position. It is connected with the cup member 32, which cup member has the flange 31 and projections 34, and therefore moves with it. The plate 19 is directly connected to the locking cylinder which is rotated by the key. The key turns through a complete revolution and simultaneously therewith the plate 19 is moved through a full revolution or 360°. It is so designed that the bar or tail piece 36, at times, is free to rotate independently of the plate 19; at other times, the plate 19 may be rotated without turning the cup member or the bar 36 connected therewith; and at other times said plate 19 and cup member will be connected together so that they will turn simultaneously. The escapement mechanism provides for such movements so that the bar 36 is rotated about its axis not more than 180°, while the key and the parts directly connected with it, turn through a complete rotation for bringing the key back to the position at which it was inserted, stopping it at such position and thereby providing for its ready removal. The finger 39 carried by the ring 38, connects the rotating plate 19 with the lock bolt operating bar 36 when said finger is in proper position to engage the projections 34 and, thus, becomes a coupling member between the driving plate 19 and the cup 32. However, when the finger 39 is moved outwardly of said projections, that is, into the lateral enlargement 41a of the housing 41, the lock bolt operating bar 36 is disconnected from the plate 19.

In the operation, said finger 39 is automatically shifted in position with the shifting of the ring 38. This shifting of the ring 38 is controlled by the inclined sides of the projection at 21, by the curvature at the side edges or first cams and inner portions of the downward projection 23 of the ring 22 above the stop shoulder, one at each edge thereof, and by the inclined sides or cam surfaces at the ends of the projections 34.

The bolt is either fully projected or fully retracted upon a turning through of approximately 180° of movement of the bolt operating bar 36, and by means of the structure allowing approximately 180 degrees escapement, a complete rotation of the key is provided. But after such movement is made in either direction, it is necessary that means be provided to force outwardly the finger 39 to disengage the projections 34 and bar 36. Should these be left in an operatively connected position to each other, it would be impossible to rotate the manual lock bolt operating member 7 at the inside of the door, because such rotation would be stopped by the locking action of the lock at the outside of the door. Therefore, to accomplish this, the plate 19 has the triangular projection 21. The apex of the projection 21 is within the periphery of said plate and is beveled at both sides. Therefore, rotation of the plate 19 in the opposite direction to which it has been turned, will bring a beveled side of the projection 21 in contact with the finger 39. The finger 39 is held frictionally by the ring member 24 in the position to which it has been moved with a resistance greater than the lateral force generated when said beveled edge of the finger 21 engages the finger 39. Thus, the finger 39 is moved

outwardly into the enlarged portion 41a of the housing 41.

After the lock has been operated, for example, by the key at the outside, the finger 39 will come to rest against the stop at 23 (Fig. 16). Immediately before it comes to this stop, there is a partial movement outwardly of the finger 39 caused by the finger's riding over the rounded or concave side edge of the projection 23 prior to coming to the stop. A completion of this outward forcing of the finger 39 is further accomplished by a beveled edge of a projection 34 on the flange 31 of the cup member. This is required in order that the lock bolt may be operated from the inside of the door. Under such condition, the flange 31 of the cup member is turned, and not the plate 19, but in either case, there is this necessary movement of the floating ring member 38 to force or cam out the finger 39 to the position shown in Fig. 17.

There is thus provided a mechanism permitting independent movement of the manually operable thumb member 7 at the inside of the door, except when the key is inserted in the lock at the outside; and with a key at the outside there is allowed a complete rotation through 360 degrees with an escapement or lost motion of 180 degrees of its movement, during which movement of the lock bolt does not occur. Such mechanism further provides for disengagement after the 180 degrees of effective movement for actuating the lock bolt has taken place, whether done by the manually operable thumb member 7 at the inside or by the key on the outside. And further, such construction provides for certainty of proper installation, not requiring a set relation between component parts. There is eliminated any need for indicating arrows or other indicia in the structure for information to the installer.

With the construction described, the assembly of the parts is simple and easy. Furthermore, the installation on the door may be made by any carpenter whether or not he is familiar with the lock structure and its operation. If he turns the housing plate 10 upside down from the position shown in Fig. 2 it signifies nothing so far as the operation is concerned, except the key is inserted in the barrel 11 reversed from the position at which it would be inserted with the escutcheon and tumbler lock right side up. If the parts housed within the housing wall at 41 have, for any reason, moved relative to each other, key manipulation will take care of it without any jamming of the parts and with an automatic positioning of them where they should be in relation to each other. No indicating directions on the mechanism are required for installer to follow which, if present, many times are not seen, and are ignored with present structures used; whereby attempting to attain operation of a night lock when the old structures when wrongly installed results in jamming inoperativeness upon attempted key operation.

The invention is defined in the appended claims and is to be considered comprehensive of all forms of structure coming within their scope.

I claim:

1. In a structure as described, a housing of substantially cylindrical form laterally offset at one side, the ends of said housing being spaced apart and having openings therethrough, a key operated lock having a rotatable barrel extending through one end of the housing, a circular plate connected at the inner end of the barrel at a side thereof having spaced recesses cut therein with

a pointed projection having inclined sides between the recesses, a cup member having an angular flange with diametrically opposite projections extending from said flange located against said circular plate and free to move rotatably relative thereto, a bar connected with the cup member extending through the other end of the housing, and a floating member having a central opening located over the cup member and against the inner side of last mentioned end of the housing having a finger at one side extending longitudinally of the housing, said floating member being movable bodily in the housing to enter said laterally projecting portion of the housing or in another position extending into a notch of said plate connected to the barrel, and come against the projections extending from the flange of the cup member, substantially as and for the purposes described.

2. A construction as defined in claim 1, said plate, at the side thereof located against said barrel, having a circular projection, a ring located over said projection, at a side thereof having a radially extending portion, the outer edges of which are inwardly curved toward each other for a short distance, and outwardly of said inwardly curved portions provided with stop shoulders, and means for securing said ring against movement.

3. A construction as defined in claim 1, said plate at the side thereof to which it is attached to the end of the barrel having a centrally disposed projection of circular form, a ring of flat metal located over said projection, at one side thereof having an outwardly extending radial portion the edges of which are curved inwardly toward each other for a short distance, and said portion beyond said curved edges being formed with opposite stop shoulders, said projection having a recess therein extending from the central opening in the ring partially through said projection, and a tongue connected with the first mentioned end of the housing extending inwardly into said projection to hold the ring against movement.

4. In a structure as described, a housing member of substantially cup form having a bottom with an opening therethrough and substantially cylindrical sides, at one portion thereof offset outwardly, a floating member having an opening therethrough located against the bottom of the housing and provided with a finger extending therefrom substantially parallel to the axes of the housing, a cup member having a circular annular flange therearound and diametrically opposed projections extending from the flange, said cup member extending through said opening in the floating member and the opening in the bottom of the housing, the opening in the floating member being greater in area than the cross section of said cup member, a bar connected with said cup member extending through the floating member and the bottom of said housing member, a circular plate located against the flange of said cup member and formed at one side with two spaced recesses and a triangular projection pointed at its outer end between said recesses, a ring located against the opposite side of said plate, said plate having means for mounting of the ring thereon, and said ring at one side having an outwardly extending radial portion having concaved edges at the inner part thereof and shoulders at the outer part thereof at each side edge, and said projection having a slot therein, a member of spring material of ring-like form located at the outer side of said ring and pro-

vided at one side with a laterally projecting portion connected with but distorted from the plane of the remainder of the member and adapted to be received in said laterally extending portion of the housing, a housing end plate located against the outer side of the spring member having a central opening therethrough and a tongue extending therefrom through the spring member into the slot of the said ring member, said end plate and first housing member being permanently secured together.

5. A construction as defined in claim 4, and a key operated barrel lock having an outer housing and a barrel rotatably mounted therein, said barrel extending through said opening in said housing end member, through said spring member to the circular plate, means for permanently connecting said rotatable barrel to the plate, and means carried by said housing end member for maintaining it against movement.

6. In an actuating structure for a key operated lock having a rotatable barrel and a reciprocable bolt, the combination comprising: a driving member fixed to said barrel and rotatable therewith; an actuating member connected to said bolt for reciprocating same; a coupling member; a first lost motion connection between said driving member and said coupling member; a second lost motion connection between said coupling member and said actuating member, said first lost motion connection and said second lost motion connection together being adapted to permit 180° of lost motion between the driving member and the actuating member when the driving member is rotated 360°; a fixed stop for engaging said coupling member; cams adapted to engage said coupling member and to release said coupling member from said stop.

7. In an actuating structure for a key operated lock having a rotatable barrel and a reciprocable bolt, the combination comprising: a driving member fixed to said barrel and rotatable therewith; an actuating member connected to said bolt for reciprocating same; a coupling member; first cams for disengaging said coupling member from said actuating member when said actuating member is rotated with respect to said driving member; a first lost motion connection between said driving member and said coupling member; a second lost motion connection between said coupling member and said actuating member, said first lost motion connection and said second lost motion connection together being adapted to permit 180° of lost motion between the driving member and the actuating member when the driving member is rotated 360°; a fixed stop for engaging said coupling member; a second cam adapted to engage said coupling member and to release said coupling member from said stop.

8. In an actuating structure for a key operated lock having a rotatable barrel and a reciprocable bolt, the combination comprising: a driving member fixed to said barrel and rotatable therewith; an actuating member connected to said bolt for reciprocating the same; a lost motion connection between said driving member and said actuating member, including a coupling member having an arm thereon, a pair of shoulders on said driving member and a pair of oppositely spaced wings on said actuating member, said arm being adapted to engage said shoulders and said wings; a fixed stop for engaging said arm; a cam on said driving member adapted to release said arm from said stop.

9. In an actuating structure for a key operated

lock having a rotatable barrel and a reciprocable bolt, the combination comprising: a driving member fixed to said barrel and rotatable therewith; an actuating member connected to said bolt for reciprocating the same; a lost motion connection between said driving member and said actuating member including a coupling member adapted for rotation and for radial movement, a fixed guide adapted to restrain said coupling member against radial movement and to permit radial movement thereof at one position in said coupling member's rotation; said coupling member having an arm thereon; a pair of shoulders on said driving member and a pair of oppositely spaced wings on said actuating member; a fixed stop for engaging said arm in said one position of said coupling member; a cam on said driving member adapted to release said arm from said stop.

10. In an actuating structure for a key operated lock as defined in claim 9 wherein a resilient element is provided; said resilient element engaging said coupling member in its said one position of rotation and adapted to restrain rotation of said coupling member when engaged by said cam.

11. In an actuating structure for a key operated lock having a rotatable barrel and a reciprocable bolt, the combination comprising: a driving member fixed to said barrel and rotatable therewith; a rotatable actuating member connected to said bolt for reciprocating same; a coupling member having an arm thereon, said arm being the only means for transmitting motion between said driving member and said actuating member; said coupling member adapted for rotary and radial movements; a fixed guide adapted to restrain said coupling member against radial movement; a radially extending pocket on said fixed guide adapted to permit radial movement of said coupling member when said arm is aligned therewith; a fixed stop aligned with said pocket; a pair of opposed wings on said actuating member having cam surfaces on the outward ends thereof; a cam surface on each side of said stop adapted to urge said arm radially outwardly into radial alignment with the cam surfaces on said wings; a pair of spaced shoulders on said driving member for engaging said arm; a radially projecting cam between said shoulders, said projecting cam adapted to disengage said arm from both said stop and either of said wings when one of said wings and said arm are both aligned with said pocket.

12. In an actuating structure for a key operated lock having a rotatable barrel and a reciprocable bolt, the combination comprising: a driving member fixed to said barrel and rotatable therewith; a rotatable actuating member connected to said bolt for reciprocating same; a coupling member having an arm thereon, said arm being the only means for transmitting motion between said driving member and said actuating member; said coupling member adapted for rotary and radial movements; a fixed guide adapted to restrain said coupling member against radial movement; a radially extending pocket on said fixed guide adapted to permit radial move-

ment of said coupling member when said arm is aligned therewith; a pair of opposed wings on said actuating member; said wings having parallel edges adjacent said actuating member and bevelled edges remote from said actuating member; a pair of cam surfaces having a fixed stop therebetween and aligned with said pocket; said cam surfaces adapted to urge said arm radially into said pocket and out of driving engagement with said parallel edges of said wings, whereby said bevelled edges on said wings may urge said arm further radially outwardly; a cam on said driving member adapted to urge said arm radially into said pocket and out of engagement with said fixed stop; means on said driving member for engaging and driving said arm upon rotation of said driving member in either direction.

13. In an actuating structure for a key operated lock having a rotatable barrel and a reciprocable bolt, the combination comprising: a driving member fixed to said barrel and rotatable therewith; a rotatable actuating member connected to said bolt for reciprocating same; a coupling member having an arm thereon; means on said driving member for engaging said arm in either direction of rotation of the driving member; means on said actuating member for engaging said arm in either direction of rotation of the arm; a cam at one position in the path of rotation of said coupling member adapted to disengage said arm from said means on said actuating member whereby said actuating member may be rotated independently of said coupling member and said driving member.

14. In an actuating structure for a key operated lock having a rotatable barrel and a reciprocable bolt, the combination comprising: a driving member fixed to said barrel and rotatable therewith; a rotatable actuating member connected to said bolt for reciprocating same; a coupling member having an arm thereon; means on said driving member for engaging said arm in either direction of rotation of the driving member; opposed projections on said actuating member for engaging said arm; said projections having parallel sides adjacent said actuating member and bevelled sides remote from said actuating member; a pair of fixed cams having a stop therebetween; said cams adapted to disengage said arm from the parallel edges of said projections on said actuating member and said bevelled edges of said projections adapted to disengage said arm from said projections whereby said actuating member may be rotated independently of said coupling member and said driving member; a cam on said driving member adapted to disengage said arm from said stop.

HERBERT QUIGLEY.
